FILIFORM GUIDE

Floyd C. Hendrickson, Canton, Ohio

Application June 15, 1938, Serial No. 213,787

2 Claims. (Cl. 128—358)

The invention relates to the class of surgical instruments known as filiform guides or "bougies," used for the purpose of exploring and for treating strictures of all kinds.

5 The object of the invention is to provide an unbreakable, smooth, non-injurious instrument, slightly less flexible than the standard type so as to be more easily inserted into strictures.

Another object is to provide a filiform guide 10 having a tapered, metal core made up of sections of fine wires, the wires in succeeding sections being reduced in number so as to give the desired taper to the finished article.

A further object is to provide such a core in 15 which the central wire of the core is doubled and extends the full length of the guide to form a loop at the smaller end thereof, to retain the outer rubber coating in place and provide a very small rounded point which will not injure tissues.

20 A still further object is to provide a guide of the character described in which the wire core is first wrapped with silk or very thin rubber ribbon or the like, and then dipped into latex rubber so as to provide a complete coating of 25 latex rubber.

Another object is to form the core of a mixture of spring or tempered wires and soft annealed wires, the spring wires tending to return the 30 guide to straight form after being bent and also aiding in giving the feel to the user in probing with the guide, and the soft annealed wires permitting the guide to stay in any desired bent shape temporarily.

A still further object is to provide a threaded 35 ferrule upon the larger end of the guide for connection to the end of a sound, although, if desired, the guide may be formed integrally upon the end of a sound so as to provide a sound or dilator having a filiform guide as an integral part 40 thereof.

The above objects together with others which will be apparent from the drawing and following description or which may be later referred to may be attained by constructing the improved 45 filiform guide in the manner illustrated in the accompanying drawing in which—

Figure 1 is an elevation of the improved guide; Fig. 2, an elevation of the wire core;

Fig. 3, an enlarged longitudinal sectional view 50 through the guide; and

Fig. 4, a further enlarged transverse sectional view thereof.

Similar numerals refer to similar parts throughout the drawing.

55 The improved filiform guide to which the invention pertains is built upon a tapered wire core formed of a plurality of fine wires indicated generally at 10, some of the wires being spring wire and others being soft annealed wire so as to tend to return the guide to straight form after

being bent while at the same time permitting the guide to stay in any shape into which it may be bent temporarily, and also aiding in giving the feel to the user in probing with the device.

For the purpose of giving the desired taper to 5 the core, the wires may be reduced in number in successive sections of the core from the larger end toward the smaller end thereof, as clearly shown in Figs. 2 and 3 of the drawing.

The central wire of the core indicated at 11 10 is doubled and extends the entire length of the guide having a loop 12 formed at the smaller end of the guide.

The wire core thus formed is then wrapped 15 throughout its entire length with silk, thin rubber ribbon or the like as indicated at 13 after which the wrapped core is dipped into latex rubber to form a latex rubber coating over the entire device as indicated at 14, the latex coating upon the wire loop 12 at the small end of the 20 guide to form a very small rounded tip or point 15 which will not injure tissues when probing with the guide.

The wires at the large end of the guide may be soldered or otherwise connected as indicated 25 at 16 within a ferrule 17 which may be internally screw-threaded as at 18 so as to be attached to the end of a sound or the like.

However, if desired, the filiform guide as above 30 described may be integrally attached to the end of a sound so as to provide a dilator or sound having a filiform guide as an integral part thereof.

With this construction a guide is provided 35 having the proper taper and being sufficiently small to enter any restricted area while the central wire extending to the tip of the guide and forming a loop provides a reinforcement which prevents the tip from being accidentally broken off.

I claim:

1. A filiform guide comprising a tapered core 45 formed of a central wire extending the entire length of the guide and successively shorter groups of wires surrounding the central wire and successively decreasing in length by substantially the length of the shortest group of wires, a thin flexible strand spirally wound upon the wires and a flexible body covering the core.

2. A filiform guide comprising a tapered core 50 formed of a central wire doubled upon itself and extending the entire length of the guide and forming a loop at the smaller end of the guide, and successively shorter groups of wires surrounding the central wire, said groups of wires 55 successively decreasing in length by substantially the length of the shortest group of wires, and a flexible body covering the wire core and forming a rounded point over said loop.

FLOYD C. HENDRICKSON. 60
